UNITED STATES PATENT OFFICE.

OSCAR BECKLIN, OF SEATTLE, WASHINGTON, ASSIGNOR TO BECKLIN MFG. CO., OF SEATTLE, WASHINGTON, A CORPORATION OF WASHINGTON.

GAME.

Application filed February 20, 1922. Serial No. 537,739.

To all whom it may concern:

Be it known that I, OSCAR BECKLIN, a subject of the King of Sweden, and resident of the city of Seattle, in the county of 5 King and State of Washington, have invented certain new and useful Improvements in Games, of which the following is a specification.

My invention relates to games and comprises apparatus whereby certain possible plays are selected by chance, thereby to control the movement of markers or pegs and consequently to affect the scoring of the game.

15 In its present embodiment the game is made up as a baseball game, and the markers are moved to correspond to movements of baseball players under the circumstances indicated, but it is not necessarily restricted 20 to baseball. Its principles may be applied to many games which have a series of possible plays, the plays affecting the positioning of the players or the scoring of the game.

25 An object of my invention is to produce a simple and compact game of the character described.

A further object is to provide such a game in which the selected play is certainly and 30 easily indicated.

35 A further object is the provision of a game apparatus for playing such games which is cheap to make and easy to operate, and further, one which can be taken down for storage or shipment.

40 A further object is the provision of game apparatus for games of the character described and which employ a round projectile in which provision is made for returning the projectile to the starting point.

45 My invention comprises those novel parts and combinations thereof which are shown in the accompanying drawings, described in the specification and defined by the claims terminating the same.

In the accompanying drawings I have shown my invention arranged for playing a game of baseball and in a form which is now preferred by me.

50 Figure 1 is a transverse section through the baseboard and guide illustrating the rotating disk in elevation.

Figure 2 is a longitudinal vertical section through my game apparatus.

Figure 3 is a perspective view of the scoring board.

The essential features of my game consist of a rotatable member, as the disk 1, a fixed guide 2 terminating at one end adjacent the disk 1, and a projectile 3 which is adapted to move along the guide or trough 2. The disk 1 is pivotally supported at 10 upon a suitable pivot support 11, preferably elevated above and supported from the baseboard 4. The pivot support 11 is 55 preferably removable from the baseboard 4 and to this end I secure in it a dowel pin 12 which is receivable in a socket 41 in the baseboard or in a rail 20 secured thereon. The trough 2 is formed in the upper edge 60 of the rail 20 and is preferably sloped downward away from the disk 1. The disk 1 is provided with a series of apertures 15, each aperture being provided with indications of a possible play. For playing baseball these 65 apertures will indicate "outs," "balls," "one, two and three-base hits," "home-runs" and the like. They are angularly spaced and 70 preferably equidistant from the center of rotation 10. Each is provided with a suitable closure plug, such as the corks 16. If 75 desired the corks themselves might bear the indications of possible plays instead of the disk itself.

In the board 45 at the lower end of the 80 trough 2, if this be slanted, being that end distant from the disk 1, I provide a plunger 5 which is projected towards the disk by 85 means of a suitable spring 53, and which has a handle 52 acting as a stop. The upper end of the trough 2 is aligned with the path of movement of the apertures 15 and lies closely adjacent thereto. The pivot support 11 should be spaced back of the disk 1 sufficiently to permit the plugs 16 90 to be removed from their apertures 15 before they strike the pivot support.

Play is begun by placing a ball 3 in the trough 2, by then spinning the disk 1, and by drawing back and releasing the 100 plunger 5. The ball 3 travels to the upper end of the trough and strikes either the disk 1 between the apertures 15 or the plug 16 in some one aperture. If the ball strikes

the disk itself there is no visible result and this may be taken arbitrarily as a "strike" or other common play. If the ball strikes a plug 16, however, this will be knocked from its aperture and upon stopping the rotation of the disk the character of the play thus indicated can be determined. By providing a small board 6 having indications thereon of the various bases of a baseball diamond, 10 and by employing pegs 61 to represent base runners and batsmen, it is possible to keep track of the various plays and moves occasioned thereby.

Preferably the baseboard 4 which surrounds the trough 2 and the pivot support 11 is sloped toward that end which carries the plunger 5 so that balls which have been projected toward the disk 1 are automatically returned to their starting point. A wall 22 20 prevents loss of the balls. By slanting the trough 2 in the same direction it is assured that the ball 8 will not accidentally roll forward and also that it will follow the retracted plunger to secure the full effect of 25 its release.

The principles of this game may be applied to other games, as, for instance, football. Instead of indicating possible plays in baseball the various possible plays in football 30 may be indicated upon the disk 1 and the position of the players may be varied upon a

field laid out to represent a football field instead of the baseball diamond employed upon the field 6.

What I claim as my invention is:

1. A game apparatus including a rotatable target having thereon play controlling indicia, a trough inclined upward towards said target and terminating adjacent the indicia carried by the same, means for projecting a projectile up the trough from its lower end, and a ball of greater diameter than the space between the trough and target projectile along the trough by said projecting means, and adapted by gravity 45 to remain at the lower end of the trough.

2. In a game, the combination of a rotatable disk carrying controlling indicia spaced thereabout and alternating with blank spaces, a guide having one end terminating 50 adjacent the face of said disk and of a width to include but one of said indicia, means at its other end for projecting a ball therealong towards the disk, and a ball of greater diameter than the space between trough and disk movable along said guide, and by its contact with one of said indicia or with a blank space indicating the character of the following play.

Signed at Seattle, King County, Washington, this 13th day of February 1922.

OSCAR BECKLIN:
